US0D1050594S

(12) **United States Design Patent** (10) **Patent No.:** **US D1,050,594 S**
(45) **Date of Patent:** **** Nov. 5, 2024**

(54) **HAIR REMOVAL DEVICE**

(71) Applicant: **Church & Dwight Co., Inc.**, Princeton, NJ (US)

(72) Inventors: **Gerhart P. Huy**, Hamilton Square, NJ (US); **Nicholas Garibaldi**, Princeton, NJ (US); **Jessica Rosenthal**, New York, NY (US)

(73) Assignee: **Church & Dwight Co., Inc.**, Princeton, NJ (US)

(**) Term: **15 Years**

(21) Appl. No.: **29/856,595**

(22) Filed: **Oct. 14, 2022**

(51) LOC (14) Cl. **28-03**

(52) U.S. Cl. **D28/44**
USPC ....

(58) **Field of Classification Search**

USPC **D28/9, 10, 44, 44.1, 49, 50**
CPC **A45D 26/00; A45D 26/0042; A45D 26/0047; A45D 26/0004; A45D 26/0061; A45D 26/0057; A45D 2026/008; A45D 2026/0095; A45D 26/0028**

See application file for complete search history.

(57) **CLAIM**

The ornamental design for a hair removal device as shown and described.

DESCRIPTION

FIG. 1 is a front perspective view of a hair removal device showing our new design;

FIG. 2 is a front view thereof;

FIG. 3 is a rear view thereof;

FIG. 4 is a side view thereof;

FIG. 5 is another side view thereof;

FIG. 6 is a bottom view thereof;

FIG. 7 is a top view thereof.

FIG. 8 is a front perspective view of a second embodiment of a hair removal device of the present invention showing our new design;

FIG. 9 is a front view thereof;

FIG. 10 is a rear view thereof;

FIG. 11 is a side view thereof;

FIG. 12 is another side view thereof;

FIG. 13 is a bottom view thereof; and,

FIG. 14 is a top view thereof.

The broken lines in the drawings illustrates portions of the hair removal device that form no part of the claimed design.

1 Claim, 12 Drawing Sheets
